United States Patent Office.

C. WATSON GUERRANT, OF LEAKSVILLE, NORTH CAROLINA.

Letters Patent No. 78,591, dated June 2, 1868.

COMBINED SQUARE AND CALIPERS.

The Schedule referred to in these Letters Patent and making part of the same.

TO ALL WHOM IT MAY CONCERN:

Be it known that I, C. WATSON GUERRANT, of Leaksville, in the county of Rockingham, and State of North Carolina, have invented certain new and useful Improvements in Carpenters' Tools; and I do hereby declare that the following is a full, clear, and exact description thereof, reference being had to the accompanying drawings, and to the letters of reference marked thereon, which form a part of this specification.

Figure 1 represents a front view of my improved machinist's tool; and

Figure 2 a back view of the same.

The nature of my invention consists in constructing a tool which can be used either as inside calipers, outside calipers, try-square, bevel-gauge, compasses, or rule, and combining in one simple instrument the properties of the six above named.

My improved machinist's tool is composed of two bars of brass or other suitable metal, A B, united near their centres by the pivot D. The bars are each cut half way through, so that their top and bottom edges will always be flush. A slotted arm, C, is pivoted to one end of the bar A, and a set-screw, b, on the adjacent end of the bar B moves in the slot c of the arm C. A curved slot, a, with radius struck from the centre of the pivot d, receives the set-screw b when the tool is used as a bevel-gauge.

It will be seen that the edges x x of the depressions made in the bars A B are square with the sides of the bars, so as to hold them at right angles when used as a try-square.

e e' represent the compass-points, f f' the inside caliper-points, and g g' the outside caliper-points. H is the rule. The divisions marked upon the slotted arm C render the outside calipers self-registering.

To use the tool as a try-square, the bars A B are moved upon the pivot until their sides strike the edges x x, which causes the angles at a' and b' to be right angles. When used as a bevel-gauge, the bars A and B are closed, and the slotted arm C, working upon the pivot d, can be set at any desired inclination, and retained by the set-screw b.

The manner of using the compasses, inside and outside calipers, and rule is self-evident upon inspection, being the same as in ordinary use, but it will be remarked that the outside calipers are made self-registering by the gauge marked upon the slotted arm C.

Having thus fully described my invention, what I claim therein as new, and desire to secure by Letters Patent, is—

The combination of the bars A and B, and slotted arm C, arranged and operating as described, for the purposes set forth.

In testimony that I claim the foregoing as my own, I affix my signature in presence of two witnesses.

C. WATSON GUERRANT.
